UNITED STATES PATENT OFFICE.

HIRAM A. KIMBALL, OF PHILADELPHIA, PENNSYLVANIA.

MACHINE FOR COUPLING BUTT-JOINTS OF SPLINTS.

SPECIFICATION forming part of Letters Patent No. 276,142, dated April 17, 1883.

Application filed February 1, 1883. (No model.)

To all whom it may concern:

Be it known that I, HIRAM A. KIMBALL, a citizen of the United States, residing at Philadelphia, in the county of Philadelphia and 5 State of Pennsylvania, have invented a new and useful Improvement in a Machine for Coupling Butt-Joints of Splints, of which the following is a specification.

The nature of my invention will be understood by the following description.

In the accompanying drawings, which make a part of this specification, Figure 1 is a front elevation of a press for coupling the splints by means of thin metallic clasps M. Fig. 2 is 15 a vertical longitudinal section at the line xx of Fig. 1; Fig. 3, a plan view of the press. Fig. 4 is a horizontal section at the line yy of Fig. 2. Figs. 5 and 6 are sectional views, on an enlarged scale, of the dies J and J' and 20 plunger L in connection with a contiguous part of the press. Figs. 7 and 8 are face and edge views, respectively, of a clasp, M, also on an enlarged scale. Fig. 9 shows coupled ends of 25 two splints. Fig. 10 is a perspective view of the plate K.

Like letters of reference in all the figures indicate the same parts.

A is the top of a bench, upon which my improved press is secured.

30 B is the bed-plate of the press, which is provided at its front edge with cheeks $a a$, which project from its under side.

C is a lever, which is hung between the said cheeks by means of the fulcrum-pin b.

35 D is a standard, which projects from the said bed-plate B, and has cheeks $a' a'$, between which the lever C' is hung by means of the fulcrum-pin b'.

E is a treadle, which is hung on the fulcrum-pin b² between the cheeks $a^2 a^2$ of the permanent block G. The treadle operates the levers C and C' simultaneously, being connected with the former by means of the rod H and joint-pins c c and with the latter by means of the 45 pitman I and joint-pins c' c', as shown in Fig. 2.

J is a stationary die connected with the permanent plate K, and J' a movable die, which is caused to slide in the slot or groove d, formed in the upper side of the plate K, as seen more 50 clearly in Fig. 10, and the under side of the die J. The said die J' receives its forward movement, for bending the edges of the clasp here-

inafter described, by means of the lever C, after which, as the lever recedes therefrom, it is returned to its former position (shown in full 55 lines in Fig. 4) by means of the spring N.

L is a plunger, which has its vertical movements in the groove f in the front edge of the standard D, being held in place by means of the cap-plate g. It is connected at its upper 60 end with the front end of the lever C' by means of the pin h.

The dies J and J' are provided with curved edges, as shown in the drawings, for bending the edges of the clasp M over the edges of the 65 splints O O, and the end of the plunger L is provided with a concave face for pressing the end down upon the convex side of the splints. The end of the plunger is also slotted to admit of its springing tightly between the edges 70 of the dies, so as to firmly press the edges of the clasp onto the splints. The clasp M is struck out of thin sheet metal, and has serrated edges, as seen clearly in Fig. 7, and has the edges curved upward to facilitate its connection with the splints, as seen in Fig. 9. 75

The operation of coupling the splints is as follows: A clasp, M, is laid between the dies J and J', with its turned-up points upward, and the operator presses the treadle E downward, 80 whereby a simultaneous movement is given to the levers C and C', the former pressing the die J' toward the die J, so as to firmly bend the serrated edges of the clasp M over the edges of the contiguous ends of splints, the curved 85 edges of the dies being of suitable shape for that purpose, and the plunger pressing the edges of the clasp down upon the convex surface of the splints and embedding the pricks i therein, to form a positive coupling of the 90 splints and an even surface of the connected parts. It will really appear that the rounded corners which constitute the upper portions of the curved surfaces of the dies J and J' facilitate the spring of the jaws j j of the plunger 95 L into place when forced down between the dies. After the clasping operation, when the operator relieves the treadle E of the pressure of his foot, the rear end thereof, overbalancing its front end, descends to its former position 100 away from the coupled ends of the splints by means of spring N, as seen in dotted lines in Fig. 5. The full lines in said figure represent the dies J and J' and plunger L in the posi-

tion they assume at the completion of their work in coupling the splints.

I claim as my invention—

- 5 1. A machine for coupling butt-joint splints with metallic clasps M, consisting of a stationary die, J, and a movable die, J', having curved edges, and a plunger, L, having a concave and slotted end, as shown, the movable die and plunger being operated by suitable means, sub-
10 stantially as described, and for the purpose set forth.
2. A machine for coupling butt-joint splints,

consisting of a movable die, J', and a stationary die, J, and plunger L, having a concave and slotted end, operated by the levers C and 15 C', actuated by the treadle E, rod H, and pitman I, for bending the clasp M around the contiguous ends of the splints O O, substantially as shown, and for the purpose set forth.

HIRAM A. KIMBALL.
